BRUSH

Charles H. Magers, Princeton, N.J., assignor to Johnson & Johnson, a corporation of New Jersey

Filed Apr. 27, 1960, Ser. No. 60,346

Term of patent 14 years

(Cl. D86—10)

Fig. 1 is a side elevational view of a brush showing my new design;

Fig. 2 is a top plan view thereof;

Fig. 3 is an end elevational view as seen from the bristle end; and

Fig. 4 is a sectional view thereof taken along the lines 4-4 of Fig. 2.

The essential features of my design reside in the portions shown in solid lines on the drawing.

I claim:

The ornamental design for a brush, as shown and described.
